UNITED STATES PATENT OFFICE.

NORMAN B. OBBARD, OF PITTSBURGH, PENNSYLVANIA.

TRUSS.

Application filed December 12, 1927. Serial No. 239,421.

This invention relates to built-up metal trusses and the like and more particularly to light weight metal trusses for use as floor joists, rafters, purlins, steel poles and similar structural purposes where strength and light weight are required.

One object is to provide a structure of this type which is composed of few parts and can be readily assembled.

Another object is to provide a structure of this type with an efficient and positive interlock at points where the component parts join or intersect, and to construct the truss so that this interlocking effect will increase as the load increases.

In the drawings—

Figure 1 is a side elevation of a truss supported between two wall sections.

Figure 2 is a perspective plan view showing details in the punching of the top chord members of Figure 1.

Figure 3 shows perspective views illustrating the way in which the ends of the web members of the trusses are cut, bent and interlaced in constructing a truss embodying my invention.

Figure 4, shows perspective views illustrating the way the ends of the web members of Figure 3 are interlocked with and secured to the chord members in constructing the truss of Figure 1.

Figure 5 is a side elevation and Figure 6 a plan of the end bracing members of the web of the truss of Figure 1.

Figure 7 is a perspective view showing details in the construction of the lower spacing piece, and Figure 8 is a similar perspective showing details in the construction of the upper spacing piece of my improved truss.

Figure 9 is a diagrammatic plan showing the assembled parts forming the truss and Figure 10 is a similar plan showing the same parts after the chord members have been received lengthwise relatively to one another in constructing the truss.

Referring more particularly to the drawings, the letters A and B designate the top and bottom chord members as a whole, which are joined by diagonal lacing members 2 and 50 end braces 3.

The chords A and B are shown composed of rolled metal angle shapes 4 and 5, arranged back to back in spaced relation to permit the lacing and bracing members 2 and 3, respectively, to be mounted therebetween. It

will be understood, however, that channels or other shapes may be used to form the chord members, if desired.

The lacing members 2 which form the web of the truss may be formed from bars, angles or other sections or shapes, and have their ends flattened, as at 7, so as to extend into the space between the shapes forming the chords.

The flattened ends 7 of the lacing members are cut or recessed to form integral tongues 8 which are bent at right angles to the body of the lacing members so as to project through suitable apertures or slot-like openings 9 in the shapes 4 and 5 forming the chords when the truss is assembled.

After the lacing members 2 are completed they are interlocked. That is, they are arranged in their diagonal position with their ends 7 overlapping and with the tongues 8 on one lacing member extending oppositely to and into the spaces between the tongues of the other lacing member.

After the lacing members are thus assembled they are assembled with the chord members A and B by passing the tongues 8 through the openings 9 in the shapes 4 and 5 and moving the members 4 and 5 lengthwise relative to each other. This relative lengthwise movement of the shapes 4 and 5 forces the shapes 4 and 5 to move inwardly along the tongues 8 toward each other and locks the whole assembly together. The tongues 8 may then be pressed or hammered down against the back walls of the shapes 4 and 5 to form a permanent structure.

It will be noted also that when the parts are thus assembled the tongues 8 of the lacing members will be brought approximately opposite each other, so that when the tongues are subsequently pressed or hammered down a tight joint will result.

In order to prevent the shapes 4 and 5, forming the chord members A and B, from sliding back and allowing the joints to open up such shapes must be locked in position.

This may be accomplished by various well known means, such as riveting or bolting, but preferably said shapes will be held in place by the self-locking end braces 3, shown in the drawings, which braces lock the pairs of shapes 4 and 5, forming the chords, together with a force which increases as the load increases.

The end braces 3 are preferably formed from an angle section bent to fit the truss.

The terminal ends 15 of the braces 3 extend parallel with the chords A and B of the truss and are adapted to extend into the space between the shapes 4 and 5 forming the chords. The terminal ends 15 are cut to form integral tongues 16 which are alternately bent in opposite horizontal positions so as to extend through suitable slots or openings 17 in the chord shapes 4 and 5. The 10 tongues 16 extend on an angle to the vertical center line of the truss so that when the truss is assembled they will tend to exert opposite forces on the shapes 4 and 5 and thereby lock said shapes in position.

15 The end braces 3 are disposed on a less slope or inclination than the diagonal lacing members 2 and, therefore, the tension in the braces 3 will be large and the projections or tongues 16 will be forced to draw the shapes 4 and 5 together with increasing force as the load on the truss increases, thus locking the whole truss together. The tongues 16 it will be understood will be preferably bent or hammered down when the truss is assembled.

20 25 Suitable spacing or filler pieces 19 and 20 are provided at the points where the end braces 3 join or connect with the top and bottom chords A and B to completely fill the space between the shapes 4 and 5. The upper 30 spacing piece is preferably formed from a short length of angle and cooperates with the upper terminal end of the end braces 3 to form a seat 21 upon which the truss end rests.

35 The method of assembly of the truss is shown in Figures 9 and 10. These figures show diagrammatically, by the arrows 23, the longitudinal movement necessary to assemble the top chord shapes 4 and 5. A similar movement is also necessary to assemble the bottom chord shapes 4 and 5. The manner in which the self-locking ends are fitted is also illustrated in these figures.

40 From the above it will be readily understood that I have provided a light weight truss structure which may be readily assembled, is cheap to manufacture, and embodies maximum strength for its weight.

45 While I have only illustrated one specific embodiment of my invention it will be understood that I do not wish to be limited thereto since various modifications may be made without departing from the scope of my invention, as defined in the appended claims.

I claim—

50 55 1. A truss structure composed of top and bottom chord members, each of said chord members being composed of a pair of rolled angle shapes arranged in spaced relation back to back, a plurality of diagonal lacing members connecting said upper and lower chord members, said lacing members having their ends projecting into the space between the rolled shapes forming said chord members, said shapes being provided with spaced apertures in their backs, and integral tongues on

said lacing members adapted to project through said apertures to lock said chord members and lacing members together.

2. A truss structure composed of top and bottom chord members, each of said chord members being composed of a pair of rolled angle shapes arranged in spaced relation back to back, a plurality of diagonal lacing members connecting said upper and lower chord members, and end bracing members extending diagonally between said top and bottom chord members, said end bracing members being provided with a plurality of integral tongue members which project through suitable apertures in said chord members to lock said end bracing members and chord members together, and said bracing members having a lesser inclination than said lacing members.

3. A truss structure composed of top and bottom chord members, each of said chord members being composed of a pair of rolled angle shapes arranged in spaced relation back to back, a plurality of diagonal lacing members connecting said upper and lower chord members, and end bracing members extending diagonally between said top and bottom chord members, said end bracing members having a lesser inclination than said lacing members, said lacing members and said bracing members having their ends projecting into the space between the backs of said rolled shapes forming said chord members, said shapes being provided with spaced apertures in their backs, and integral tongues on said lacing members and said bracing members which project through said apertures to lock said lacing members, bracing members and chords together.

4. A truss structure composed of top and bottom chord members, and diagonal lacing members connecting said chord members, said lacing members being interlocked at their ends with each other and with said chord members.

5. A truss structure composed of top and bottom chord members, and diagonal lacing members connecting said chord members, said lacing members being provided with integral tongues at each end, the tongues on said lacing members being interlocked with the tongues of the next adjacent lacing member and with said chord members.

6. A truss structure composed of top and bottom chord members, each of said chord members being composed of a pair of rolled angle shapes arranged in spaced relation back to back, a plurality of diagonal lacing members connecting said upper and lower chord members, said lacing members having their ends projecting into the space between the backs of said rolled shapes forming said chord members, said shapes being provided with spaced apertures in their backs, said lacing members being provided with integral tongues extending at right angles to the

longitudinal axis of said lacing members, said tongues on said lacing members being interlocked with the tongues of the next adjacent lacing member and projecting through 5 said apertures in said shapes forming said chord members, and means for locking said shapes forming said chord members against relative longitudinal movement.

7. A truss structure composed of top and 10 bottom chord members, each of said chord members being composed of a pair of rolled metal angle shapes arranged in spaced relation back to back, a plurality of diagonal lacing members connecting said upper and 15 lower chord members, said shapes forming each of said chord members being provided with a series of spaced apertures in their back walls, said lacing members having their ends projecting into the spaces between the 20 backs of said rolled shapes forming said chord members and being provided with integral tongues at each end which extend through some of said apertures in said chord members, and end bracing members having 25 top and bottom terminal portions extending parallel with and into the space between the backs of said rolled shapes forming said chord members, said terminal portions being provided with a plurality of integral tongues 30 extending at substantially right angles to the vertical axis of said chord members and on an angle to the vertical center of said truss, said tongues being projected through other of said apertures in said rolled shapes whereby 35 said rolled shapes will be automatically locked in position by said end bracing members when said structure is assembled.

8. A truss structure composed of top and bottom chord members, each of said chord members being composed of a pair of rolled 40 metal angle shapes arranged in spaced relation back to back, a plurality of diagonal lacing members connecting said upper and lower chord members, said shapes forming each of said chord members being provided 45 with a series of spaced apertures in their back walls, said lacing members having their ends projecting into the spaces between the backs of said rolled shapes, forming said chord members and being provided with integral tongues at each end which extend through some of said apertures in said chord members, and end bracing members having 50 top and bottom terminal portions extending parallel with and into the space between the backs of said rolled shapes forming said chord members, said terminal portions being provided with a plurality of integral tongues 55 extending at substantially right angles to the vertical axis of said chord members and on an angle to the vertical center of said truss, said tongues being projected through other of said apertures in said rolled shapes whereby 60 said rolled shapes will be automatically locked in position by said end bracing members when said structure is assembled, and all of said tongues on said lacing and bracing members being bent down parallel with the 65 walls of said rolled shapes through which they are projected to form a permanent 70 structure.

In testimony whereof, I have hereunto signed my name.

NORMAN B. OBBARD.
